[57] **CLAIM**

The new and ornamental design for a pen clip, as shown and described.

DESCRIPTION

FIG. 1 is a front elevational view of a pen clip showing my new design;

FIG. 2 is a left side view thereof;

FIG. 3 is a right side view thereof;

FIG. 4 is a rear view thereof;

FIG. 5 is a top plan view thereof; and,

FIG. 6 is a bottom plan view thereof.

The broken line showing of the ring member for securing my new pen clip to a pen is for illustrative purposes only and forms no part of the claimed design.

FIG. 5

FIG. 1

FIG. 2

FIG. 3

FIG. 4

FIG. 6
